UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,858, dated April 11, 1882.

Application filed March 8, 1882. Term of patent 3½ years.

To all whom it may concern:

Be it known that I, ARTHUR L. HALLIDAY, of New York, N. Y., have invented a new and original Design for Carpets, of which the following is a specification.

This invention relates to a new and original design for carpets, oil-cloths, and similar fabrics.

It consists in the novel grouping and configuration of parts hereinafter more fully described.

The accompanying photograph illustrates a face view of a carpet having my new design.

The letter H represents a slender branch, bearing on it circular flowers and serrated leaves.

D is a flower figure containing a central bunch of circular flowers surrounded by leaves, and having projecting at one side a slender stem, o, resembling a species of grass, and bearing hanging bell-shaped grass-like projections. On the other side of the figure D projects a branch bearing circular flowers and small leaves.

A is a flower group having projecting from it, on one side, the branch e, bearing leaves shaped like clover-leaves, and on another side the branch f, bearing projecting deeply-serrated leaves, and from still another side the branch g, bearing flowers divided into numerous slender projections.

C resembles a bunch of flowers surrounded by projecting leaves.

B is a flower group having a center of open flowers, and projecting therefrom, on one side, the branch i, bearing leaves divided into numerous points, and on the other side the branch k, bearing a circular flower and clover-like leaves.

The figure a consists of a slender branch having on it a few scattered circular flowers and nearly devoid of leaves, with a background of small circles set closely together.

m is a background figure composed of a series of small rectangular figures shaped like a capital S, set closely together.

v is a figure for the background, composed of a series of small figures, forming incomplete parallelograms, interposed with dots and set closely together.

d is a branch projecting into the field of the pattern and bearing circular flowers and sparsely-scattered serrated leaves.

I claim—

1. The design for carpets, consisting of figure H, substantially as shown. 55

2. The design for carpets, consisting of figures D and o, substantially as shown.

3. The design for carpets, consisting of figure C, substantially as shown. 60

4. The design for carpets, consisting of figure m, substantially as shown.

5. The design for carpets, consisting of figures A e f g, substantially as shown.

6. The design for carpets, consisting of figure a, substantially as shown. 65

7. The design for carpets, consisting of figure d, substantially as shown.

8. The design for carpets, consisting of figure v, substantially as shown. 70

9. The design for carpets, consisting of figures B k i, substantially as shown.

ARTHUR L. HALLIDAY.
